(57) **CLAIM**

The ornamental design of a support arm for transformer table, as shown and described.

DESCRIPTION

FIG. 1 is a perspective view of the support arm for transformer table of the present invention;

FIG. 2 is a left side elevational view thereof, the right side elevational being a substantial mirror image thereof;

FIG. 3 is a front elevational view thereof;

FIG. 4 is a bottom plan view thereof.

FIG. 5 is a rear elevational view thereof; and,

FIG. 6 is a top plan view thereof.

The broken line showing of environmental structure in FIGS. 1 and 3 is for illustrative purposes only and forms no part of the claimed design.
